TIMING SELECTOR FOR CAMERAS HAVING ELECTRONIC TIMERS

BACKGROUND OF THE INVENTION

The field of the invention is photography, particularly cameras having shutters with a delayed releaser.

The invention relates to a timing selector for cameras with electronic timers consisting of an RC member comprising a stepped rheostat with a mechanically movable contact member for setting the time constants. An example of this prior art timing selector is disclosed in West German printed Specification 1,263,492 of Franz Starp, which issued Mar. 14, 1968.

Another apparatus for electronic exposure control in photographic cameras is disclosed in British Patent 1,086,300, of Reimann et al., which issued Oct. 4, 1967. According to the disclosure of Reimann et al. there are two timing cycles cooperating with one another. These are used in the case of self portraits, etc. The exposure time switching system is set in operation after the expiration of the delayed action time.

SUMMARY OF THE INVENTION

The object of this invention is to provide a timing selector with a large timing range which is operative directly with the "B" camera setting and having any desired length of closure time.

The problem of increasing the timing range is solved in the present invention by providing a movable contact member with at least two contact arms which are brought successively into engagement with the contacts up to a transitional region so as to bridge over any possible gaps by having each contact arm come into electric connection with an associated capacitor of such a size that the time constant of one contact arm for the transitional region is about the same as the time constant for the other contact arm, and so that the capacitors will be disconnected from one another.

BRIEF DESCRIPTION OF THE DRAWINGS

The invention will be more readily comprehended by reference to the accompanying drawings, wherein:

FIG. 1 is a schematic representation of the circuit of the timing selector;

FIG. 2 shows in section a particular modification of the mechanical construction of this timing selector; and

FIG. 3 shows a section on the line III-III of FIG. 2.

DESCRIPTION OF THE PREFERRED EMBODIMENTS

The electronic timer is best explained by reference to FIG. 1, wherein a battery 1 is connected by a switch 34 to a stepped rheostat 2 consisting of separate resistors 3 and contacts 4, 5 and 6. The stepped rheostat 2 is arranged along an arc whose inner angle is smaller than 180° C. A rotatable setter 10 carries two switch arms 11 and 12 which form a conductive path between contacts 4, 5 and 6 and contact paths 13 and 14. In their intermediate positions the ends of the switch arms bridge over the gaps between neighboring contacts. The contacts do not permit any open circuits so that a motor connection is possible with the rotatable setter in any angular position.

Contact path 13 is electrically connected to a capacitor 20 and contact path 14 to a capacitor 21. The electric charge which at times appears at capacitor 20 or 21 is conducted by a discharge circuit to a terminal 22 which serves as the input for an electronic control circuit for shutter actuation. The discharge circuit is shown in the drawing as consisting of two diodes 23 and 24 but can consist of transistors or other rectifying elements. Parallel to the stepped rheostat 2 there is an electrically connected resistor 30, in series with a contact 31 adjacent a sliding point 32 which is electrically connected by a switch 33 with the capacitor 20. The switches 33 and 34 are controlled by a disconnecting key (not shown) so that when the disconnecting key is depressed, the switch 33 will first be opened and then the switch 34 closed, whereas when the key

is released first the switch 33 will be closed and then the switch 34 opened.

The sliding arms 11 and 12 of the rotatable setter 10 are fixed in relation to one another and subtend an angle α_2 which is slightly smaller than the central angle α_1 . When the sliding arm 11 arrives upon one of the last contacts 6 of the stepped rheostat 2, then the sliding arm 12 arrives at the first contact 4 of the series. As can be seen from FIG. 1, the sliding track 13 is slightly longer than the sliding track 14, so that when the last contact 6 is reached, only the sliding arm 11 keeps contact 6 electrically connected to capacitor 20, whereas when sliding arm 12 arrives at contact 6, no such electric connection is maintained with capacitor 21.

The apparatus of FIG. 1 functions as follows: Assuming that the sliding arm 11 is upon the first contact 4 of the series, when the shutter-release key is depressed so as to close the battery switch 34, the capacitor 20 will become charged in the shortest possible time across resistor 3'. This time constant corresponds to the shortest possible closing time of the shutter, e.g. 1/2000 second. If the sliding arm 11 is moved toward the position shown in FIG. 1, the RC time constant becomes progressively longer and so does the shutter closing time. Besides the normal exposure times, intermediate values can be set. When the sliding arm 11 has arrived at contact 6 the sliding arm 12 arrives at the first contact 4. The capacitor 21 is of such a size that together with the first partial resistor of the stepped rheostat 2, an RC member will be formed whose time constant will correspond to that of the sum of the partial resistors of the stepped rheostat 2 and capacitor 20, thereby permitting the exposure time to be increased to about 1/25 second. In actual practice when the sliding arm 12 moves upon first contact 4, only the capacitor 21 will be charged. By the making of such a contact a certain timing error may be introduced so that the angles α_1 and α_2 do not need to be exact and continuous contact maintained to obtain satisfactory functioning of the timer, as during motorized actuation. If now the rotatable setter is turned further, the sliding arm 11 will be moved beyond its operative range and the charging of the RC member will be across the sliding arm 12 and the relatively larger capacitor 21 will become charged and the relatively longer exposure times from 1/8 to 1/16 second retained.

As has been mentioned before it is the purpose of the present timing selector to provide a certain voltage at the terminals 22 at certain preestablished time periods (shutter time) after actuation of the shutter-release key. The voltage obtained from the terminals is supplied to an electronic shutter control device known per se which causes the shutter to be closed whenever this certain voltage is reached. It should particularly be noted that the opening of the shutter is performed purely mechanically by pressing the shutter-release key, and only the closing of the shutter is achieved by means of the electronic control device.

Having this in mind it will be apparent that special means must be provided for shutter closing after a so called "B" exposure, this being the exposure whereby the shutter is opened upon pressing of the shutter release key, where it stays open as long as the key remains depressed, and where it is closed upon removing the finger from the key, i.e. upon release of the key.

The means provided for performing this function comprise a further contact 31 being arranged at the end of the rheostat and being connected by way of a resistor 30 directly to the battery 1. Associated with contact 31 is a sliding point 32 which is connected by a switch 33 to the low-capacitance capacitor 20. Contact 31 and sliding point 32 are disposed relative to one another in such a way that upon setting the timer to the B setting sliding arm 11 establishes an electrically conductive connection between the contact and the sliding point. By this connection capacitor 20 is in effect connected to battery 1 and would become charged if switch 34 would be closed. The latter, however, remains open until the shutter-release key is pressed. Then switch 34 is actually closed, since switch 34 is mechanically connected to the shutter-release key so as to be closed when the key is actuated and to be opened when the key is released, as has been mentioned before.

Upon actuation of the shutter-release key capacitor 20 would actually become charged, were it not for switch 33 which is also mechanically coupled to the shutter-release key so as to be opened upon key actuation, which switch opening occurs just prior to the closing of switch 34. Thus, even if the shutter-release key is pressed capacitor 20 is still not charged because switch 33 has been opened. And it is not until the shutter-release key is released that also switch 33 is closed while switch 34 is still closed, as a consequence whereof capacitor 20 is now charged in a very short time, thus providing the necessary voltage at the terminals 22 for the closing of the shutter.

The working phases of the switches 33, 34 during shutter key actuation being thus:

shutter key pressing: first switch 33 is opened, then switch 34 is closed,

shutter key release: first switch 33 is closed, then switch 34 is opened, and thereafter switch 33 is also opened.

In the overlapping period of time when both shutters are closed capacitor 20 is charged within fractions of a second. The mechanical coupling of the switches 33, 34 to the shutter-release key need not further be described since it is considered a matter of simple design which is within the knowledge of anyone skilled in this type of design work.

FIGS. 2 and 3 show a modification of the timer on an enlarged scale. It consists of two platelike ring discs 7 and 8 and the rotatable setter 10 with its arms 11 and 12 whose free ends are bifurcated. The sliding arms 11, 12 comprise two electrically connected fingers 15, 16 and 17, 18 which are arranged in spaced apart planes. The ring disc 8 carries on one side of it an electric resistance layer from which resistors 3 are formed, and on its other side the contacts 4, 5 and 6 which are electrically connected with the resistance layer 3 by rivets 9. The plate 7 has the slideways 13 and 14 mounted on the inner side of it. Fingers 15 and 16 are electrically connected to each other. The sliding contact surface of finger 16 is wide enough to bridge over the space between successive contacts 4 and 6.

In FIG. 3 the paths 13 and 14 of the contact arms and the rotatable setter 10 are indicated in dot and dash lines. The time setter has a potentiometer 40 built into it and coupled to it to compensate for film sensitivity and diaphragm setting for determining the exposure time.

The fingers of sliding arms 11 and 12 are provided with cooperating knobs so that one arm will be in engagement with contacts 4, 5 or slideways 13, 14, while the other arm is out of engagement therewith, and that in the transitional range at contact 6, both arms will be in engagement with these parts.

We claim:

1. A timing setter for cameras having an electronic timing circuit containing an RC member which includes a stepped rheostat and a mechanically movable timing setter for setting the time constant, the improvement comprising:

- a plurality of contacts (4,5,6) on said rheostat;
- a first capacitor (20) having a given capacitance contained in said RC member;
- a second capacitor (21) having a greater capacitance

than said given capacitance contained in said RC member; and

5 d. said timing setter having a plurality of sliding arms (11,12) the first of which is electrically connected with said first capacitor and the second of which is connected with said second capacitor, said first and second sliding arms spaced from one another and having successive bridging connection with said contacts and a transitional range wherein the time constant of the first sliding arm is about the same as that of said second sliding arm while said capacitors are uncoupled from one another.

2. The timing setter of claim 1, wherein said contacts of the rheostat are arranged along an arch whose subtended angle α_1 is less than 180° and said spaced first and second sliding arms 15 define an internally subtended angle α_2 which is smaller than said angle α_1 .

3. The timing setter of claim 2, further comprising a first slideway (13) on said rheostat connecting with said first sliding arm (11) and a second slideway (14) on said rheostat connecting with said second sliding arm (12), the slideways being of different angular extents.

4. The timing setter of claim 3, wherein said sliding arms (11,12) comprise two electrically connected fingers (15,16,17,18) arranged in spaced apart planes and said contacts (4,5,6) and said slideways (13,14) are arranged in similarly superimposed planes.

5. The timing setter of claim 3, wherein said first sliding path (13) is connected with said first capacitor (20) and said second sliding path (14) is connected with said second capacitor (21) and said first slideway is longer than said second slideway.

6. The timing setter of claim 5, wherein said sliding arms are sufficiently broad to bridge successive contacts whereby the rheostat is stepped and the RC member provides means for 35 giving a shutter intermediate closing times in addition to normal gradations.

7. The timing setter of claim 6 in combination with a camera having a B setting, and further comprising electric means in the circuit of the low-capacitance capacitor (20), said means being deenergized upon actuation of said shutter actuator and being energized upon release of said shutter actuator for charging said capacitor in a short period of time after shutter actuator release.

8. The timing setter of claim 7, wherein said means com-

45 prise a contact (31) in addition to said contacts of the stepped rheostat, said contact (31) being electrically connected to the battery (1) by way of a resistor (30), a sliding point (32) being arranged adjacent to said contact (31), said sliding point being electrically connected to said capacitor (20), and said contact

50 and said sliding point being electrically connected by said first sliding arm (11) when said timing setter (10) is set to said B setting, and a normally closed switch (33) between said sliding point (32) and said capacitor (20), said switch being mechanically connected to said shutter operator so as to be opened upon actuation of said shutter operator prior to closing of the battery switch (34).
